Euclid I. La Chapelle

UNITED STATES PATENT OFFICE.

EUCLID I. LA CHAPELLE, OF BROCKTON, MASSACHUSETTS.

METHOD OF PREPARING OUTERSOLES FOR BOOTS AND SHOES.

Application filed July 21, 1922. Serial No. 576,509.

To all whom it may concern:

Be it known that I, EUCLID I. LA CHAPELLE, a citizen of the United States, residing at Brockton, in the county of Plymouth 5 and Commonwealth of Massachusetts, have invented certain Improvements in Methods of Preparing Outersoles for Boots and Shoes, of which the following description, in connection with the accompanying drawings, is a specification.

My invention relates to outersoles for boots and shoes and more particularly to outersoles having greater elevation at one lateral side than at the opposite lateral side. 15 The foot, generally speaking, has the tendency to "roll" toward the little toe side of the boot or shoe and, in due course of time, is thereby weakened. My invention has for object the provision in outersoles for boots 20 and shoes of a raised portion over the plane surface thereof to counter-act this objectionable tendency and to cause the foot to tread in the center of the boot or shoe bottom and to cause the weight of the body to be mainly 25 supported upon the great toe and upon the ball back of the great toe while the heel is lifted in the act of walking.

With this aim in view, I have invented the herein disclosed method invention, 30 which is primarily intended for use on leather but which may be adapted to material other than leather.

In the drawings:

Fig. 1, is a plan view of an outersole for 35 a boot or shoe embodying my invention.

Fig. 2, is a transverse sectional view of the outersole shown in Fig. 1, illustrating more particularly my novel method step of forming a raised portion at one thereof.

Fig. 3, is a sectional view taken on line 40 3—3 of Fig. 1, illustrating more particularly a filler contained in the cavity of the outersole shown in Fig. 1.

Fig. 4, is a plan view similar to the one 45 shown in Fig. 1, but with a fabric cover strip shown as applied to the outersole over the filler in the cavity.

Fig. 5, is a sectional view taken on line 50 5—5 of Fig. 4.

Fig. 6, is a perspective view of the outersole shown in Fig. 4.

In Fig. 1, the outersole 1, is shown with a cavity 2, formed therein under the influence of the force applied to the plane surface of the outersole in the practice of my method invention. In Fig. 2, the outer-

sole is shown as having been formed with a bevel raised portion 3, under the influence of the forcing action of the moulds 4 and 5, and as shown, the said bevel raised portion is located within the marginal portion 6, of the outersole, which marginal portion is intended for receiving the fastenings required in the process of uniting the outersole to the shoe. In Fig. 3, is shown a sectional view similar to that of Fig. 2, but with the addition of a filler 7, shown as applied into the cavity in the outersole, and which serves to retain the bevel raised portion of the outersole in raised condition during wear 70 and which is preferably held into the cavity by cementitious material. In Fig. 5, is shown a sectional view taken on line 5—5 of Fig. 4, illustrating a fabric cover strip 8, which is applied to the outersole over the 75 filler in the cavity and which is held there-to preferably by cementitious material, whereby the filler is held into the cavity during wear, and, as shown, extending from side to side of the outersole over the marginal portion 6, so that the fastenings required in the process of uniting the outersole to the shoe will pass through the same to positively hold the filler in the cavity during wear. 80

In Fig. 4, is shown a plan view similar to that of Fig. 1, illustrating the outersole 1, the cavity 2, containing the filler over which is applied the cover strip 8. In Fig. 6, is shown a plan view similar to that of Fig. 1, 90 illustrating the reversed side, or outside plane surface of the outersole, the bevel raised portion 3, and the edge of the fabric cover strip 8, located on the opposite plane surface of the outersole. 95

The outersole, as herein shown, is in the form adapted to welt shoes, it being rough rounded to the shape of the shoe once having been laid on the shoe, but it must be appreciated that my invention is adaptable to 100 and is intended for outersoles embodying the shape of the shoe prior to being incorporated into the shoe such as ordinary outersoles for McKay shoes.

In the case of such outersoles as leather 105 outersoles, water, or other liquid, is preferably applied and thereafter, while the outersoles are under the effect of the liquid, (preferably while in temper) force is applied to one side by means of moulds, as herein 110 shown, or by other suitable means, whereby the plane surface at one of the lateral sides

of the outersole (preferably at the little toe side, as herein shown) is forced above the opposite lateral side of the outersole. Once dry, the filler, which may be of a composition adaptable to be moulded in proper corresponding form of the cavity in the outersole, is applied into the cavity and then the cover strip, which is preferably of fabric, is applied over the outersole and over the filler

10 in the cavity.

I am well aware that, for the same purpose as herein contemplated, it is old in the art of shoe repairing to form by hand and unite to the little toe sides of outersoles of boots and shoes by means of nails or stitches bevel shaped patches, corresponding to the herein shown bevel raised portion 3, integral with the outersole 1, (see Fig. 6) and it is the sole purpose of my present invention to 15 improve upon the mode of uniting such bevel shaped patches to outersoles by integrally embodying the same in outersoles, and my invention is thus limited and the claims are to be interpreted to forcing on a 20 bevel the plane surface of a sole to form thereby a beveled surface corresponding, in length and width, substantially to the bevel shaped patch common to the art of shoe repairing. Extending approximately from the 25 toe-end to the ball-line and from the edge to the middle longitudinal line of the sole, for the purpose of causing the wearer of the boot or shoe to tread on the center of the sole; and the novel construction of the mould 30 4, (see Fig. 2) is adapted to and intended for such integral embodiment.

As herein shown, the bevel raised portion 3, is formed inwardly of the marginal portion of the outersole, so that uniformity 35 in heft of outersole edge will exist at both sides of boots and shoes. Experiments have shown that the said bevel raised portion should be about three sixteenths of an inch at its thickest part. Furthermore, the outer- 40 sole should be laid on a shoe for best results so that the said bevel raised portion will be in close proximity to the finished bottom edge of the shoe.

The term "outersole", occurring in the

specification and in the claims must be interpreted to include a half outersole in the form of a tap, as well as a full outersole. The term "shoe", occurring in the specification and in the claims, must be interpreted to include the term "boot".

Having thus described my invention, what I claim as new and desire to secure by Letters Patent is:

1. The method of preparing outersoles for boots and shoes, which consists in forcing on a bevel the plane surface of an outersole at one of its lateral sides above the plane surface of its opposite lateral side and in the application of a filler into the cavity formed in the outersole under the influence 65 of said forcing action, for the purposes described.

2. The method of preparing outersoles for boots and shoes, which consists in forcing on a bevel the plane surface of an outersole at one of its lateral sides above the plane surface of its opposite lateral side and within the marginal portion of the outersole, in the application of a filler into the cavity formed in the outersole under the influence 75 of said forcing action and in the application of a material over the filler in the outersole, for the purposes described.

3. The method of preparing outersoles for boots and shoes, which consists in forcing on a bevel the plane surface of an outersole at one of its lateral sides above the plane surface of its opposite lateral side, in the application of a filler into the cavity formed in the outersole under the influence of said 80 forcing action and in the application of a material extending from side to side of the outersole over the filler in the outersole, for the purposes described.

4. The method of preparing soles for boots and shoes, which consists in forcing on a bevel the plane surface of a sole at one of its lateral sides above the plane surface of its opposite lateral side, for the purpose of causing the wearer of the boot or shoe to 95 tread on the center of the sole.

EUCLID I. LA CHAPELLE.
